UNITED STATES PATENT OFFICE

2,636,175

BODY SUPPORTED PERSPIRATION
ABSORBING DEVICE

George R. Hoffman, Jr., Eau Claire, Wis.

Application August 14, 1950, Serial No. 179,249

1 Claim. (Cl. 2—55)

1

This invention relates to a novel construction of perspiration absorbing device including a pad adapted to be detachably supported in the arm-pit for absorbing perspiration and which is readily detachable from its supporting means to enable the pad to be disposed of and replaced with a fresh pad after it has become saturated.

More particularly, it is an aim of the present invention to provide a device of this character of extremely simple construction capable of being readily adjusted to different body sizes and wherein a pad may be quickly and easily applied to or removed from its supporting means.

Still a further object of the invention is to provide a pad which may be very economically manufactured and sold and which is adapted to be impregnated with a deodorant.

Still a further object of the invention is to provide a perspiration absorbing device including supporting means of extremely simple construction capable of being comfortably and conveniently worn beneath outer garments.

Various other objects and advantages of the invention will hereinafter become more fully apparent from the following description of the drawing, illustrating a presently preferred embodiment thereof, and wherein:

Figure 1 is a front elevational view of a portion of the human body showing two of the perspiration absorbing devices in applied positions;

Figure 2 is an enlarged perspective view of one of the devices shown removed from the body;

Figures 3 and 4 are enlarged longitudinal sectional views taken substantially along planes as indicated by the lines 3—3 and 4—4, respectively, of Figure 2;

Figure 5 is an enlarged perspective view of one end of the supporting means or suspender, and

Figure 6 is an enlarged plan view of the absorbing pad.

Referring more specifically to the drawing, the perspiration absorbing device in its entirety is designated generally 7 and includes an absorbent pad 8 and a suspender, designated generally 9.

The pad 8 is adapted to be formed of any highly absorbent material which is relatively inexpensive and preferably is composed of a filler 10 of cotton enclosed in an envelope 11 of gauze or other porous material, or any other suitable combination of absorbent materials may be employed. The pad 8 is substantially rectangular in shape and is provided with flattened end portions 12 which are spaced from the side edges

2

thereof and which flattened portions are suitably reinforced, as by being compressed or by any other suitable means, so that an opening 13 which is formed in each flattened portion 12 and which is spaced a considerable distance from the adjacent end of the pad 8 will not readily tear out.

The suspender 9 includes two straps 14 and 15 each composed of two plies and each of which is preferably formed by a long length of strap which is folded upon itself intermediate of its ends to form the two plies which are stitched together as seen at 16 except at their terminals to provide free terminal portions 17 and 18 at complementary ends of each of the straps 14 and 15. The terminal portion 17 of each strap is provided with a female snap fastener section 19 and the terminal portion 18 of each strap is provided with a male snap fastener section 20. The snap fastener sections 19 and 20 are secured in a conventional manner and open or project from the inner sides of said terminal portions 17 and 18. One set of terminal portions 17 and 18 is adapted to straddle each restricted pad portion 12 and is secured thereto by engaging the snap fastener sections 19 and 20 thereof through the opening 13 of said recessed portion 12, as illustrated in Figure 3, for detachably fastening the pad between the complementary ends 17, 18 of the straps 14 and 15. The straps 14 and 15 may be formed of any suitable relatively lightweight flexible material and may be relatively thin, due to their two ply construction and since they are only required to support the pad 8 which is of little weight. The opposite, folded ends of the straps 14 and 15 are detachably and adjustably connected in overlapping relationship by a slide loop 21 including end bars 22 under which the straps 14 and 15 extend and an intermediate cross bar 23 over which said straps extend, as best illustrated in Figure 4, and by which the strap ends are frictionally gripped and held in any adjusted position.

The straps 14 and 15, properly adjusted by the loops 21, form the suspender 9 which is disposed over the shoulder of the user and supports the pad 8 between the ends 17, 18 thereof, as previously described, and with the pad disposed under the arm, as clearly illustrated in Figure 1, for absorbing perspiration. The pad 8 may be completely assembled with the suspender 9 and the arm then inserted through the opening formed by the suspender and pad and the suspender moved up the arm and onto the

shoulder for positioning the pad beneath the armpit or one end of the pad may be attached to the suspender and after it is positioned over the shoulder, the strap end 17, 18 of the strap 15 may be attached to the opposite end of the pad, as previously described. The strap 15 is preferably disposed at the front of the body and is shorter than the strap 14 so that the retaining loop or fastener 21 will be disposed conveniently in front of the body where adjustments can be made in the length of the suspender. One longitudinal edge of the pad, constituting an upper edge thereof when in an applied position, is disposed against the armpit whereby the substantially flat sides of the pad are disposed between and against the body and arm, as seen in Figure 1. The strap ends which engage the pad ends are twisted relatively to the intermediate portion of the suspender whereby said strap ends extend upwardly and inwardly from the pad to resist outward sliding movement of the suspender relatively to the shoulder of the wearer.

The pad 3 is adapted to be impregnated with a deodorant and it will be readily apparent that the pad can be very economically manufactured and sold so that it provides a disposable pad which can be thrown away after becoming saturated with perspiration. It will also be apparent that one of the devices 7 will be supported on each shoulder and with the pads thereof disposed beneath each armpit.

Various modifications and changes are contemplated and may obviously be resorted to, without departing from the spirit or scope of the invention as hereinafter defined by the appended claim.

I claim as my invention:

A perspiration absorbing device consisting of a shoulder engaging suspender adapted to be disposed over the shoulder and having a pair of separated ply portions at each end thereof, a pad adapted to be disposed in the armpit and extending from front to back of the body, said pad being substantially flat and having a lon-
